DESIGN FOR A HINGE

Walter R. Lustig, Rockford, Ill., assignor to The Atwood Vacuum Machine Company, Rockford, Ill., a copartnership composed of Seth B. Atwood and James T. Atwood

Application April 19, 1935, Serial No. 56,469

Term of patent 14 years

To all whom it may concern:

Be it known that I, Walter R. Lustig, a citizen of the United States, residing at Rockford, in the county of Winnebago and State of Illinois, have invented a new, original, and ornamental Design for Hinge, of which the following is a specification, reference being had to the accompanying drawing, forming part thereof.

In the drawing:

Figures 1 and 2 are perspective views of the

hinge embodying my invention looking at it from opposite sides;

Figs. 3 and 4 are a top view and an end view, respectively, and

Figs. 5 and 6 are side elevations corresponding to Figs. 1 and 2, respectively.

I claim:

The ornamental design for a hinge, substantially as shown.

WALTER R. LUSTIG.
